D. L. WINTERS,
GAS ENGINE ATTACHMENT.
APPLICATION FILED APR. 19, 1918.

1,275,117.

Patented Aug. 6, 1918.

UNITED STATES PATENT OFFICE.

DAVID L. WINTERS, OF PHILADELPHIA, PENNSYLVANIA.

GAS-ENGINE ATTACHMENT.

1,275,117.

Specification of Letters Patent. Patented Aug. 6, 1918.

Application filed April 19, 1918. Serial No. 229,577.

To all whom it may concern:

Be it known that I, DAVID L. WINTERS, a citizen of the United States, residing at Philadelphia, in the county of Philadelphia and State of Pennsylvania, have invented certain new and useful Improvements in Gas-Engine Attachments, of which the following is a specification.

This invention relates to gas engine attachments, and more particularly to devices or means adapted to be associated with or connected to the intake manifold of the gas engine for atomizing and breaking up the entering explosive compound.

One of the objects of the present invention is to provide a simple and practical attachment of the above general character having relatively few parts which may be inexpensively manufactured. A further object is to provide an attachment of the above character adapted to break up the explosive compound or the globules of gasoline passing through the intake manifold, thereby to obtain a better explosive compound, to prevent carbonizing of the cylinders, and to generally increase the efficiency of the engine. A further object is to provide a simple device of the above character which may be easily applied by the owner of the machine without the aid of skilled mechanics, thereby to increase the mileage obtainable from the same quantity of gasoline. A further object is to provide a device of the last above mentioned character so composed and constructed as to permit its adaptability to various types of engines now in general use.

Other objects will be in part obvious from the annexed drawings and in part indicated in connection therewith by the following analysis of this invention.

The invention accordingly consists in the features of construction, combination of parts and in the unique relations of the members, and in the relative proportioning and disposition thereof, all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure,

and in such drawings like characters of reference denote corresponding parts throughout all the views, in which—

Figure 1 is a side sectional elevation of a part of a carbureter and intake manifold showing the invention applied thereto;

Fig. 2 is a similar view showing the same device applied to a different type of manifold;

Fig. 3 is a perspective view of the device shown in either Figs. 1 or 2 in its manufactured form;

Figs. 4 and 5 are detail perspective views showing modifications.

Referring now to the drawings in detail, and more particularly to Fig. 1, 6 denotes a carbureter of any desired type provided with a throttle valve 7, and connected in the usual manner at 8 with an intake manifold 10 of an internal combustion engine. This type of intake manifold it will be noted is provided with a curved elbow and in this elbow between the throttle valve and the inlets to the cylinder is applied the attachment or atomizer shown in Fig. 3. This comprises an elongated sheet of copper webbing 11 of relatively fine mesh having a bent over projecting end 12 adapted to be clamped between the flanges of the carbureter and manifold at the connection 8. A suitable washer or gasket 13, Fig. 1, is preferably applied thereto, in order to prevent the possibilities of leakage at this point. The copper mesh is provided with and secured at any convenient point to a wire frame 14 of substantially double figure-8 conformation in order that it may conform to the diagonal cross sections of the round manifold 10. It will be clear that when this device occupies a position tangential to the inner curve of the elbow as shown in Fig. 1 a sector of the pipe at that point will be relatively narrow and gradually widen out in elliptical form in the center of the manifold and then gradually taper in toward the points 15 and 16.

The peculiar construction of this device will thus effectively close the intake manifold in two planes, thus compelling the explosive mixture passing from the carbureter to the cylinders to penetrate two layers of thickness of this copper mesh in directions, as indicated by arrows. This action very

effectively breaks up all globules of gasoline and atomizes the same, causing an effective intermingling of the elements composing the explosive compound.

5 It has been found by actual tests that a device of this character so applied will increase the mileage of an automobile substantially twenty per cent. on the same quantity of fuel.

10 In Fig. 2 there is shown the carburetor 6 and an intake manifold 17 formed of substantially straight piping. The same device shown in Fig. 3 may be applied to this type of manifold just as easily; the only difference being that it is bent at substantially right angles at the point 18. The two elliptical portions formed by the wire 14 will thus effectively close the intake manifold, compelling the explosive compound to pass 15 through the mesh in planes at substantially right angles to each other, and thus accomplish the same results, that is thoroughly atomizing the gasoline and producing a more intimate mixture of the air and gas 20 forming the explosive compound.

The wire 14 which is preferably of semi-resilient material readily permits the same device to be applied to either type of intake manifold. The edges 20 of the mesh are of 25 such light and easily distorted material that they will conform to the configuration of the pipe under all conditions and insure a tight connection about the outline of the wire 14 for manifolds of slightly different 30 internal diameter.

In Fig. 4 an attachment of the same construction as that above described is shown except that it is permanently secured to a gasket or packing member 21, which may 35 be clamped between the flange of the manifold and carburetor at joint 8 when the parts are assembled. In Fig. 5, instead of having a gasket or flange member 21, a small sheet metal plate 22 is used to which the mesh 11 is connected. These forms may 40 be more easily handled under certain conditions but obviously are slightly more expensive to manufacture. The operation, method of use and assembling however are 45 the same as above described in connection with Figs. 1 and 2, according to the type of manifold with which the attachment is intended to be used. The surface of the 50 screen being presented at an angle to the path of the fuel the globules of gasoline will be caused to strike the screen, and in 55 passing through the openings therein will be broken up and thoroughly commingled with the air. A further advantage of so positioning the screen is that the area of the 60 manifold is not decreased, this being due to the fact that the cross section of the screen is sufficiently greater than the cross 65 section of the manifold to afford the same area for the flow of fuel.

As a rule the manifolds employed in the construction of automobile engines are of comparatively rough casting, that is to say the bore of the same is left in rough unfinished condition. By means of the resilient frame which I employ I am enabled to insert my device within the castings, the bendable or semi-resilient material of which the same is composed enabling it to readily follow the inequalities in the casting and which, as will be obvious, would not be the case were a rigid or non-bendable frame employed.

It is thus seen that the present invention provides a simple and practical attachment, particularly adapted for use on automobiles for the purpose of more effectively breaking up the stream of the explosive compound and to insure a more efficient and better mixture, thereby increasing the efficiency of 75 the engine and the mileage obtained therefrom.

I realize that considerable variation is possible in the details of construction and arrangement of parts without departing 80 from the spirit of my invention, and I therefore do not intend to limit myself to the specific form shown and described.

Having thus described my invention what I claim as new and desire to secure by Letters Patent is—

1. The combination with the intake manifold of an internal combustion engine, of an attachment comprising a compressible frame member and a sheet of easily distortable material of relatively fine mesh mounted thereon, said frame being inserted in the manifold to cross the same at different points and to closely contact with the wall thereof, whereby to compel the repeated passage, through said mesh of the explosive compound passing through said manifold.

2. An attachment of the character described comprising a resilient frame member of double elliptical or figure-8 form, and a sheet of fine mesh gauze covering said form, said attachment being adapted to be passed into the intake manifold of an explosive engine and positioned therein to cross the bore thereof at different points, thereby to compel the repeated passage through said mesh of the explosive compound passing through said manifold.

3. An attachment of the character described comprising a frame of bendable or semi-resilient material of substantially figure-8 form, a sheet of gauze mounted thereon, and means for securing said parts in place in the intake manifold of an engine and in angular relation to the bore thereof to compel the explosive compound to pass repeatedly therethrough before reaching the cylinders.

4. In combination with a curved intake manifold of an internal combustion engine,

a relatively flat frame of substantially figure-8 form, and a sheet of gauze mounted upon said frame, said frame being mounted in the manifold and extending on opposite sides of the curve thereof, thereby to effectively close the intake manifold at two places to the free passage of explosive compound therethrough, said parts being so positioned and arranged as to compel the explosive compound to pass repeatedly through the gauze.

5. In combination with a curved intake manifold of an internal combustion engine, a relatively flat frame of substantially figure-8 form, and a sheet of gauze mounted upon said frame, said frame being mounted in the manifold and extending on opposite sides of the curve thereof, thereby to effectively close the intake manifold at two places to the free passage of an explosive compound therethrough, said parts being so positioned and arranged as to compel the explosive compound to pass repeatedly through the gauze, and means for securely 10 clamping said attachment in place within the manifold.

6. In combination with a curved intake manifold of an internal combustion engine, a relatively flat frame of substantially figure-8 form, and a sheet of gauze mounted upon said frame, said frame being mounted in the manifold and extending on opposite sides of the curve thereof, thereby to effectively close the intake manifold at two places to the free passage of an explosive compound therethrough, said parts being so positioned and arranged as to compel the explosive compound to pass repeatedly through the gauze, and means for securely 15 clamping said attachment in place within the manifold, said means including a relatively flat member to which the gauze is permanently attached.
